UNITED STATES PATENT OFFICE.

FRANK ZALESKI, OF SOMERVILLE, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

1,214,108.

Specification of Letters Patent. Patented Jan. 30, 1917.

Application filed July 6, 1915. Serial No. 38,185.

To all whom it may concern:

Be it known that I, FRANK ZALESKI, a subject of the Emperor of Germany, residing at Somerville, county of Middlesex, 5 State of Massachusetts, have invented an Improvement in Buttonhole-Sewing Machines, of which the following description, in connection with the accompanying drawing, is a specification, like characters on the 10 drawing representing like parts.

This invention relates to buttonhole sewing machines and has for its objects to provide a novel work clamp which is simple in construction and operates to clamp the work 15 and hold under tension that portion thereof in which the buttonhole is to be formed, and also to provide a novel means for cutting the upper and under thread at the end of the stitching operation on a buttonhole, and for 20 clamping or gripping the severed end of the upper thread so as to hold it while the stitching operation is commenced on the next succeeding buttonhole.

While my invention is capable of use with 25 buttonhole sewing machines of different types, I have herein chosen to illustrate it as it might be embodied in a buttonhole sewing machine of the so-called "Reece" type, examples of which are to be found in the following United States patents: No. 494,280, dated March 28, 1893; No. 655,637, dated 30 August 7, 1900; No. 1,030,589, dated June 25, 1912.

In order to give an understanding of my 35 invention I will now describe a selected embodiment thereof and will then point out the novel features in the appended claims.

Figure 1 of the drawings is a side view of 40 a portion of a buttonhole sewing machine of the "Reece" type having my improvements applied thereto; Fig. 2 is a plan view of the work clamp showing the thread-cutting and clamping devices; Fig. 3 is a view similar to Fig. 1, but showing the parts in the position 45 they assume just prior to the cutting and clamping of the thread; Fig. 4 is a section on the line 4-4, Fig. 3; Fig. 5 is a section on the line 5-5, Fig. 3; Fig. 6 is a plan view of a portion of the under clamping 50 member; Fig. 7 is a section on the line 7-7, Fig. 3; Fig. 8 is a side view of Fig. 3; Fig.

9 is a plan view of the thread-gripping member.

Sewing machines of the so-called "Reece" type such as are illustrated in the above-mentioned patents, are provided with a clamp frame 1 having work-clamping means and a so-called stitch frame 2 which carries the stitch-forming instrumentalities which are usually in the form of an upper and under thread mechanism. The upper thread mechanism includes the needle bar 3 carrying the needle 4 which controls the upper thread 5, said needle bar not only having the usual reciprocating motion, but also a rotative motion to effect the stitching around the ends of the buttonhole, such rotative motion being given from the shaft 6 which carries a sector 7 meshing with a pinion 8 through which the needle bar operates. The under 70 thread mechanism which is also carried by the stitch frame is provided with suitable means for controlling the under thread 9 and concatenating it with the upper thread and includes in its construction a throat-plate 10 through which the thread passes. The parts as thus far described are or may be all as shown in the above-mentioned patents and as they form no part of my present invention I have not deemed it necessary to 80 further illustrate them.

In the construction shown in the above-mentioned patents the work-clamping means comprises two clamp plates and two work-clamping members movable toward and 85 from the clamp plates and operating to clamp the work between them. The two clamp plates, as well as the two work-clamping members, are arranged to present a space between them in which the stitch-forming 90 instrumentalities operate to stitch the buttonhole, and said devices are constructed so that when the machine is started the work-clamping members will be moved toward the clamp plates thereby to clamp the work 95 between them and then the clamp plates will be separated slightly to place the portion of the work in which the buttonhole is to be stitched under tension.

I have shown herein a work-clamping device which comprises an under and an upper member, each of which presents a unitary

element provided with an aperture through which the stitching instrumentalities operate to stitch the buttonhole and which have coöperating means that result in stretching 5 the portion of the work spanning said aperture when the two members are brought into operative clamping position relative to each other.

The under work-clamping member is 10 shown at 11, and the upper member at 12. The under clamping member is shown as secured to a plate 13 which is removably sustained on the clamp frame in a manner similar to that in which the clamp plates of the 15 above-mentioned patents are retained in position. The upper clamping member 12 is secured to and carried by an arm 14 pivoted at 15 to the plate 13. This arm 14 is similar in construction to the arms illustrated in the 20 above-mentioned patents that carry the work clamps, and it has integral therewith the hook-shaped extension 16 that is engaged by an element (not shown) forming part of the usual means by which the work clamps 25 are raised and lowered, said means operating as described in the above-mentioned patents to depress the arm 14 and thus bring the upper clamping member into operative position automatically when the machine is 30 started. The under clamping member 11 is provided with an aperture 18 of a size corresponding to the buttonhole to be, stitched and the upper clamping member 12 is provided with a similar aperture 19, said apertures forming the space through which the 35 stitch-forming instrumentalities operate to effect the formation of the buttonhole stitches.

In the operation of a buttonhole sewing 40 machine it is essential that the portion of the work *w* in which the buttonhole is to be stitched should be held tightened or under some tension during the stitching operation, and I provide for subjecting the 45 work to the required tension by providing one of the clamping members with a tensioning rib or flange surrounding the aperture and which fits into the aperture in the other clamping member. In the present embodiment of my invention this tensioning flange is formed on the upper clamping member 50 12 and is shown at 20, it being formed immediately circumjacent the aperture 19 and extending entirely thereabout. The aperture 18 in the under member is of sufficient size to receive the tensioning flange 20, as shown in Fig. 4. When the work is 55 placed between the clamping members and the upper member is closed down onto the lower member, the tensioning flange 20 engages the upper face of the work and forces the portion thereof spanning the aperture and in which the buttonhole is to be formed down through the aperture 18, and by this 60 operation such portion of the work is placed

under sufficient tension so that the buttonhole stitching will be properly formed therein.

The work-clamping members have associated therewith means for severing the upper and under thread and for gripping or clamping the severed end of the upper thread. This thread-cutting and clamping mechanism is constructed to operate at the end of the stitching operation on the buttonhole, but before the machine has been brought to rest.

It will be understood by referring to the above-mentioned patents that the buttonhole sewing machines illustrated therein are 80 so constructed that when the machine is set in operation the stitch frame and clamp frame have a movement relative to each other before the stitching operation begins, during which movement the work is 85 clamped and the stitch-forming instrumentalities are brought into proper position to begin stitching operations on the buttonhole. This is illustrated in Fig. 1 wherein the full line position of the needle bar shows 90 the position of the parts when the machine is at rest and the dotted line shows the relative position when the stitch-forming instrumentalities have been brought into proper position to commence the stitching 95 on the buttonhole. During the stitching of the buttonhole the clamp frame and stitch frame have a further relative movement to carry the stitches down one side of the buttonhole, around the end thereof and back 100 up the other side of the buttonhole, and when the buttonhole is completed, the stitching instrumentalities are brought to rest with the needle 4 raised and in approximately the dotted line position Fig. 1. The 105 stitch frame and clamp frame then have a further relative movement to restore the parts to the full line position Fig. 1, during which time the upper clamping member 12 is released and elevated, thereby unclamping the work.

My improved thread-cutting and clamping mechanism is designed so that it is rendered operative to cut the thread and clamp the upper thread during this final relative movement of the stitch frame and clamp frame and after the upper clamping member 12 has been released and raised into its elevated position.

The thread-cutting device is herein shown 120 as mounted on the under clamping member 11 and it comprises a cutting knife 21 slidably mounted in a guideway 22 formed on the under clamping member and coöperating with a cutting block 23 fixedly secured 125 to the under clamping member. The under clamping member is provided with a thread-receiving slot or groove 24 in the end of the opening 18 which is closed normally by the cutting blade 21 when the latter is resting 130

against the cutting block 23. When the cutter 21 is withdrawn from the cutting block 23, however, this slot 24 is opened for the reception of the threads.

It will be understood that when the stitching operation on a buttonhole is completed and the stitch-forming mechanism is in the dotted line position Fig. 1, the under thread 9 leading from the work to the throat-plate 10 is at the forward end of the aperture 18 in the under clamping member 11. It will also be understood by reference to said above-mentioned patents that at the completion of the stitching on a buttonhole the stitch-forming instrumentalities will be brought to rest with the needle 4 raised, and with the last-formed loop 25 of needle thread extending from the work through the throat-plate 10 and around a looper element 26 of the under thread mechanism and back to the work again. The under thread 9, of course, extends directly from the work through the throat-plate 10 to the under thread mechanism. Hence both the upper thread 5 and the under thread 9 extend from the work *w*, through the throat-plate.

As stated above, after the stitching on the buttonhole is completed the stitch frame and work frame have a relative movement into the full line position Fig. 1, and during such relative movement the loop 25 of upper thread and the under thread 9 are drawn into the thread-receiving slot 24, the cutter 21 having been withdrawn to uncover said slot during such final relative movement of the frames. After the upper and under thread have entered the slot 24, the cutter 21 is given its thread-cutting movement to sever the threads. The means for operating the cutter 21 are actuated by the final relative movement between the stitch frame and clamp frame. This cutter 21 is shown as pivotally connected at 26 to a lever 27 that is pivoted at 28 to the plate 13, said lever being acted upon by a spring 29 that gives the cutter its thread-cutting movement and yieldingly holds it against the cutting block 23.

The stitch frame has secured thereto an arm or projection 30 formed with a nose 31 that is situated to engage a roll 32 carried by the end of the lever 27. This arm 30 is so constructed that when the stitch frame and clamp frame have their final relative movement shown in dotted lines Fig. 1, the nose 31 will be closely adjacent the roll 32 as seen in Fig. 2. As a result, when the stitch frame and clamp frame have their final relative movement the nose 31 engages the roll 32 and wipes by the latter, thus swinging the lever 27 against the action of the spring 29 and withdrawing the cutter 21 so as to uncover the slot 24. The threads then enter said slot and before the stitch frame and clamp frame complete their final relative

movement, the nose 31 has wiped by the roll 32 and released the lever 27, thus permitting the spring 29 to move the cutter 21 forwardly against the block 23 thereby severing both the upper and under threads.

Means are provided for gripping the upper thread simultaneously with the cutting of the threads, and such thread-gripping means is herein shown as associated with the upper clamping member 12. This upper clamping member 12 is formed with the groove 33 at the front of the aperture 19.

34 designates a thread-gripping member slidably mounted in ways in the upper clamping member 12, said member 34 being situated at the front of the aperture 19 and normally closing the groove 33. This member 34 is provided with a notch 35 which is adapted to be brought in line with the groove 33 when said member is moved laterally. Said member 34 is acted upon by a suitable spring 36 which tends normally to hold it in the position shown in Fig. 2, and said member is acted upon by a lever 37 pivoted at 38 to the arm 14. The lever 27 is provided with an arm 39 which is adapted to engage the lever 37 as the lever 27 moves, thereby turning the lever 37 in a direction to move the thread-gripping member 34 against the action of the spring and into a position to bring the notch 35 therein in line with the groove 33, as shown in Fig. 3. The construction is such that when the clamping plate 12 is in its operative work-clamping position, the lever 37 will be situated below the arm 39, as shown in full lines Fig. 8, but when the work clamp has been released and is in its elevated open position the lever 37 is in position to be engaged by the arm 39 as the lever 27 is operated, as seen by dotted lines Fig. 8. It will be seen, therefore, that when the stitching operation on the buttonhole has been completed and the work clamps have been released and brought into their elevated position, the movement of the stitch frame from the dotted to the full line position Fig. 1 will operate to swing the lever 27, as above described, thereby cutting the upper and under threads. This same movement of the lever 27 causes the arm 39 to engage the lever 37 thereby moving the thread gripping member 34 into position to bring the notch 35 therein in line with the groove 33. When this occurs, the portion of the upper thread 5 extending from the

needle to the work will be drawn into the notch 35 as the stitch frame 2 continues its forward movement. Just prior to the completion of the forward movement of the stitch frame the nose 31 of the arm 30 passes off from the roll 32 thereby releasing the lever 27, and the spring 36 then moves the thread-gripping member 34 into the position shown in Fig. 2, thereby carrying the notch 35 out of alignment with the groove 33.

33 and gripping the upper thread. The upper thread is thus firmly held when the stitching begins on the next buttonhole thereby insuring that the first stitch will be 5 perfectly formed and relieving the operator of the duty of drawing out a length of the upper thread and holding it while the first stitches are formed.

When the machine is started to stitch the 10 second buttonhole, the upper clamping member 12 is carried down into clamping position before the stitch frame and clamp frame have their relative movement and hence when during such initial relative movement 15 the nose 31 wipes by the roll 32, the resultant movement of the lever 27 is effected without operating the thread-gripping member because at this time the lever 37 is in a plane below the arm 39 and the latter merely 20 swings over the lever 37. The upper thread will, therefore, be held by the thread-gripping means during the operation of the entire buttonhole and until the stitching operation has been completed on the button- 25 hole.

I claim:

1. In a buttonhole sewing machine, the combination with upper and under thread mechanism, of work-clamping means comprising two clamping members between which the work is held continuously clamped during a predetermined stitching operation, means carried by one of said members for cutting the upper thread, and means carried by the other of said members for clamping the severed end of the upper thread.

2. In a buttonhole sewing machine, the combination with upper and under thread mechanism, of work-clamping means comprising two clamping members between which the work is clamped, means carried by one of said members for cutting both the upper and the under thread, and means carried by the other of said members for clamping the severed end of the upper thread.

3. In a buttonhole sewing machine, the combination with upper and under thread mechanism, of work-clamping means comprising an upper and an under clamping member between which the work is held continuously clamped while a plurality of stitches are being formed, means carried by the under clamping member for cutting the upper thread, and means carried by the upper member for clamping the upper thread.

4. In a buttonhole sewing machine, the combination with upper and under thread mechanism, of work-clamping means comprising an upper and an under clamping member between which the work is clamped, means carried by the under clamping member for cutting both the upper and the under thread, and means carried by the upper member for clamping the severed end of the upper thread.

5. In a buttonhole sewing machine, the combination with a stitch frame having upper and under thread mechanism, of a clamp frame, said frames being movable relative to each other, a work clamp carried 70 by the clamp frame and presenting two clamping members, a thread-cutting device carried by one clamping member, an upper thread clamping device carried by the other clamping member, and means actuated by 75 the relative movement of said frames to operate said cutting and clamping devices to cut the upper thread and clamp the severed end thereof at the end of a stitching operation. 80

6. In a buttonhole sewing machine, the combination with a stitch frame carrying upper and under stitch-forming mechanism, of a clamp frame, said frames being movable relative to each other, a work clamp 85 carried by the clamp frame and presenting upper and under clamping members, a device carried by the under clamping member for cutting the upper thread, a device carried by the upper member for clamping the 90 severed end of the upper thread, and means actuated by the relative movement of said frames to operate said devices.

7. In a buttonhole sewing machine, the combination with a stitch frame carrying 95 upper and under thread mechanism, of a clamp frame, said frames being movable relative to each other, a work clamp carried by the clamp frame and presenting upper and under clamping members, a cutting 100 knife slidably mounted on the under clamping member, a thread-clamping device slidably mounted on the upper clamping member, and means actuated by the relative movement of said frames to operate said devices. 105

8. In a sewing machine, the combination with a stitch frame carrying upper and under thread mechanism, of work-clamping means comprising two clamping members 110 between which the work is clamped, said stitch frame and work-clamping means having a movement relative to each other after the needle has been brought to rest upon the completion of a predetermined stitching operation, means carried by one of the clamping members for cutting the upper thread, means carried by the other of said clamping members for clamping the severed end of 115 the upper thread, and means operated by the relative movement between the stitch frame and work-clamping means to actuate the thread-cutting and thread-clamping mechanism.

9. In a buttonhole sewing machine, the 125 combination with a stitch frame carrying upper and under thread mechanism, of work-clamping means comprising two clamping members between which the work is clamped, said stitch frame and work- 130

clamping means having a relative movement upon the completion of a predetermined stitching operation, a device carried by one of the clamping members for cutting both the upper and the under thread, a device carried by the other of said clamping members for clamping the severed end of the

upper thread, and means actuated by the relative movement of the stitch frame and work-clamping means to actuate said devices. 10

In testimony whereof, I have signed my name to this specification.

FRANK ZALESKI.
